DESIGN FOR A CUSHION SEAT FOR TOILET COVER

Faith Hall Fielding, La Jolla, Calif.

Application December 12, 1946, Serial No. 135,435

Term of patent 14 years

(Cl. D4—5)

To all whom it may concern:

Be it known that I, Faith Hall Fielding, a citizen of the United States, residing in La Jolla, in the county of San Diego and State of California, have invented a new, original, and ornamental Design for a Cushion Seat for Toilet Cover, of which the following is a specification, reference being had to the accompanying drawing, forming part thereof.

Fig. 1 is a perspective view as seen from the top of a cushion seat for toilet cover, showing my new design.

Fig. 2 is a bottom plan view thereof.

I claim:

The ornamental design for a cushion seat for toilet cover, substantially as shown.

FAITH HALL FIELDING.
